UNITED STATES PATENT OFFICE.

GUY B. COLLIER, OF KINDERHOOK, NEW YORK.

GAS-LIGHTING APPARATUS.

1,133,267.

Specification of Letters Patent. Patented Mar. 26, 1915.

Application filed December 4, 1914. Serial No. 875,527.

To all whom it may concern:

Be it known that I, GUY B. COLLIER, a citizen of the United States, residing at Kinderhook, in the county of Columbia and State of New York, have invented certain new and useful Improvements in Gas-Lighting Apparatus; and I do hereby declare the following to be a full, clear, and exact description of the invention, such as will enable others skilled in the art to which it pertains to make and use the same.

The present invention relates to gas lighting apparatus and more particularly to apparatus of this type which automatically lights and extinguishes the main gas burner at predetermined intervals. In apparatus of this type the opening and closing movements of the gas valve are ordinarily accomplished by gravity, the actuating member being brought into a position in which it may operate by suitable time controlled mechanism. With this construction the apparatus must be permanently located in one position and any deviation from this position causes a variation in the time of lighting and extinguishing the gas, furthermore, the operation of the valve controlling mechanism may be affected by jarring or vibration sufficiently to vary the time of lighting and extinguishing the gas a considerable amount.

The object of the present invention is to provide an improved mechanism of this character which causes abrupt opening and closing movements of the valve at predetermined intervals and which will operate for a long continued period without attention.

A further object of the invention relates to certain improved constructions and arrangements whereby the assembling of the apparatus in operative position is facilitated and the timing of the opening and closing movements of the valve accurately controlled.

With these objects in view the several features of the invention consist in certain novel features of construction, combinations and arrangements of parts hereinafter described and claimed, the advantages of which will be obvious to those skilled in the art from the following description.

In the accompanying drawings illustrating the preferred form of the invention; Figure 1 is a view illustrating an elevation of the improved lighting and extinguishing mechanism; and Fig. 2 is a side ele-

vation partly in section of the mechanism shown in Fig. 1.

The present invention is preferably shown in connection with a lighting apparatus of the type shown and described in the co-pending application of applicant, Ser. No. 836,884, filed May 7, 1914. In this apparatus a timing gear 1 is actuated from a suitable clock train not shown, to make one complete rotation during each twenty-four hours. This timing gear is connected with a valve shaft 3 supported in a bearing indicated at 4 and oscillated at predetermined intervals to open and close the main gas valve in the usual manner.

The mechanism shown in the illustrated embodiment of the invention serves to impart abrupt opening and closing movements to the valve at predetermined intervals controlled by the main timing gear and independent of the position of the apparatus. To this end an actuating lever 5 is supported upon a shaft 6 and is provided with oppositely extending arms 7 and 8 which engage respectively with the operating dogs 10 and 11 adjustably secured to the timing gear 1. It will be noted from an inspection of the drawings that the engagement of the dog 10 with the arm 7 serves to rock the actuating lever to the left, and upon a continued rotation of the gear 1 the engagement of the dog 11 with the arm 8 serves to rock the actuating lever in the opposite direction. To this end the dog 11 is elongated and provided with an inturned end 12 which projects over and engages with an outwardly projecting finger 13 formed upon the arm 8. The dogs 10 and 11 serve respectively to control the time of lighting and extinguishing the main gas burner, and in order to vary these intervals as desired, the dogs are adjustably connected to the time gear. The dog 10 is secured in a circumferential slot 15 formed in the gear and projects rearwardly through the slot into a position to engage with the arm 7. The dog 11 is supported upon the gear shaft in front of the gear, as shown clearly in Fig. 2, in position to engage with the out-turned end 13 of the arm 8. Both dogs are adjusted in the usual manner through the provision of a main gear concentric with the timing gear, and small pinions connected to the dogs and engaging with the main gear.

The outer end of the actuating lever supports a suitable weight 16 which facilitates

the operating movements of the lever as hereinafter described. The actuating lever 5 coöperates with a weighted valve lever 18 which is supported upon a shaft 19 located 5 parallel to the shaft 6, and is provided with oppositely extending arms 20 and 21 formed integral therewith. The arms 20 and 21 are engaged by the lever 5 at predetermined intervals to oscillate the valve lever 18 and 10 open and close the valve. For this purpose the outer ends of the arms 20 and 21 are provided with projections 23 and 24 formed thereon, which engage respectively with the lever 5, as shown clearly in Fig. 1. The 15 actuating lever, as stated previously, has abrupt valve opening and closing movements imparted thereto and the purpose of the time gear is to move the actuating lever at predetermined intervals into a position 20 where these opening and closing movements may take place. In the illustrated embodiment of the invention when the valve is opened or closed the lever is normally retained in an inclined position and the movement 25 of the timing gear serves to gradually elevate the lever from one of these two inclined positions to a vertical position. When the lever reaches this vertical position mechanism is provided for abruptly rocking it 30 into an inclined position and at the same time actuating the valve lever 18. To this end a control member is supported in operative relation to the lever and is arranged to operatively engage with the lever to first 35 release and then move the lever at predetermined intervals. The control member serves to accurately determine the time at which the gas valve is opened and closed independently of the position of the apparatus. 40 or of external conditions which might otherwise effect the operation of the valve actuating lever. Some difficulty has been experienced with the gravity operated mechanism as with this construction external conditions 45 tending to cause a jarring or vibration of the mechanism when the actuating lever has nearly reached a vertical position will cause the operation of the lever before the predetermined time, thus varying the opening or 50 closing movements of the gas valve. As the movements of the actuating lever are relatively slow this variation may assume considerable proportions. In the present construction the controlling arm performs the 55 function of accurately determining the time at which the actuating lever is moved to open or close the valve, and further aids the weighted arms in retaining the valve in open or closed position. An arm 25 is fulcrumed 60 upon a shaft 26 supported in the back plate 27 of the machine and the arm is provided upon its free end with a wedge shaped face 28 which engages with a pin 30 projecting from the actuating lever 5. The free end of 65 the lever is normally pressed against the pin by a coiled spring 31 surrounding the shaft 26, as shown clearly in Fig. 2. With this construction, as the actuating lever is slowly elevated to a vertical position by the timing gear the pin 30 moves along one face of the wedge until the point of the wedge is reached, when a further movement causes the pin to engage with the opposite face of the wedge and an abrupt movement is then imparted to the lever by the spring 31. 70 When the actuating lever is again moved to open or close the valve, this action is repeated, the pin 30 sliding along the opposite face of the wedge until the apex is reached. With this construction it will be noted that 75 the valve opening and closing movements are imparted when the pin 30 reaches the apex of the wedge shaped face and this movement takes place independently of 80 whether the actuating lever is in a vertical or an inclined position. In order to limit the range of movement of the moving parts and permit the convenient assembling of the apparatus the valve lever 18 is provided with a slot 32 which receives a pin 33 secured in the back plate of the machine and serving to limit the oscillatory movement of the valve lever in opposite directions. In 85 order to permit the rocking movement of the valve lever 18 without causing the arm 20 to interfere with the arm 25 the controlling arm is provided with a recess 35 in its upper face, which permits the rocking of the lever to the left into an inclined position. 90

In assembling the apparatus it is desirable to have provision for adjustment of the valve shaft and valve relative to the valve lever, thus enabling the opened and closed 95 positions of the valve to be readily adjusted with relation to corresponding positions of the valve lever 18. To this end a sleeve 36 is secured to the outer end of the valve shaft by a set screw 37 and is provided with an arm 38 in which an adjusting member 39 100 is journaled. The valve shaft is connected to the valve lever by a bell crank supported upon the sleeve and having an out-turned arm 40 which engages with a slot 41 formed 105 in the actuating lever, and a second arm 42 110 which is adjustably connected with the arm 38.

It will be observed from an inspection of Fig. 2 that the time controlling and valve actuating mechanism is all supported upon the back plate 27 and is connected with the valve shaft by means of the arm 40 which is received in the slotted portion of the valve lever 18. By means of this connection the back plate carrying the entire mechanism may be readily removed and replaced whenever desired without disturbing the valve shaft and connecting arm. 115

The arm 42 is provided with a lengthwise slot 43 which receives a pin 45 mounted 120

125

130

centrically in the rotary adjusting member 39 in order that a rotation of the adjusting member shall vary the angular relation of the arms 38 and 42. The two arms frictionally engage with one another in order to retain them in any adjusted position and the adjusting member is conveniently provided with a slotted head 46 for the reception of any suitable instrumentality. With this construction the position of the valve and valve shaft 3 may be conveniently adjusted with relation to a corresponding position of the valve lever 18 to permit the ready assembling of the apparatus.

15 While it is preferred to employ the specific construction and arrangement of parts shown and described, it will be understood that this construction and arrangement is not essential except so far as specified in the 20 claims, and may be changed or modified without departing from the broader features of the invention.

The invention having been described, what is claimed is:

25 1. A gas lighting apparatus, having in combination, a valve shaft, a time gear, an actuating lever, connections between the lever and time gear for oscillating the lever in opposite directions at predetermined intervals, and mechanism for mechanically imparting abrupt movements to the lever when it is moved into a predetermined position by the time gear.

30 2. A gas lighting apparatus, having in combination, a valve shaft, a time gear, an actuating lever, a valve lever, connections between the time gear and actuating lever, mechanism for mechanically imparting valve opening and closing movements to the 35 actuating lever when in a predetermined position, and mechanism for moving the valve lever when the actuating lever is moved to open or close the valve.

35 3. A gas lighting apparatus, having in combination, a valve shaft, a time gear, an actuating lever, connections between the actuating lever and time gear for oscillating the actuating lever in opposite directions at predetermined intervals, a controlling arm 40 for the actuating lever, and means for causing the arm to impart abrupt movements to the actuating lever when it is moved into a predetermined position.

4. A gas lighting apparatus, having in combination, a valve shaft, a time gear, an actuating lever, connections between the actuating lever and time gear for oscillating the actuating lever in opposite directions at predetermined intervals, an arm pivoted at one end and having its free end positioned in operative relation to the actuating lever, a spring normally tending to press the arm against the actuating lever, and connections between the free end of the arm and the actuating lever for causing the arm to impart abrupt movements to the actuating lever.

5. A gas lighting apparatus, having in combination, a valve shaft, a time gear, an actuating lever, connections between the time gear and actuating lever for oscillating the lever in opposite directions, an arm having a wedge shaped face, a pin secured to the lever and engaging with the face, and a spring constantly tending to maintain the free end of the arm in engagement with the pin.

6. A gas lighting apparatus, comprising a time gear, an actuating lever, connections between the actuating lever and time gear for oscillating the lever in opposite directions at predetermined intervals, an oscillatory valve lever having a slot formed therein, a stationary pin received in the slot to limit the movements of the valve lever, operative connections between the actuating lever and valve lever, and mechanism for imparting abrupt movements to the actuating lever.

7. A gas lighting apparatus comprising a valve shaft, a time gear having a circumferential slot formed therein, an actuating lever, oppositely extending arms connected to the actuating lever, a dog adjustably secured in the slotted portion of the time gear and projecting rearwardly from the gear into a position to engage with one of the arms, a second dog supported in front of the gear and arranged to engage with the second arm, connections between the actuating lever and valve shaft, and mechanism for imparting abrupt valve opening and closing movements to the actuating lever.
